US0D1111170S

(12) **United States Design Patent** (10) **Patent No.:** **US D1,111,170 S**
(45) **Date of Patent:** **** Feb. 3, 2026**

(54) **DENTAL SUPPORT**

(71) Applicant: **M3 HEALTH INDÚSTRIA E COMÉRCIO DE PRODUTOS MÉDICOS, ODONTOLÓGICOS E CORRELATOS S.A.**, Jundiaí (BR)

(72) Inventors: **Marcio Luiz de Oliveira Bueno**, Rio Claro (BR); **Sybele Saska Specian**, Santana de Parnaíba (BR); **Elaine Yoshiko Matsubara**, São Paulo (BR); **Alberto Blay**, São Paulo (BR)

(73) Assignee: **M3 HEALTH INDÚSTRIA E COMÉRCIO DE PRODUTOS MÉDICOS, ODONTOLÓGICOS E CORRELATOS S.A.**, Jundiaí (BR)

(**) Term: **15 Years**

(21) Appl. No.: **29/878,751**

(22) Filed: **Jun. 27, 2023**

(30) **Foreign Application Priority Data**

Dec. 28, 2022 (BR) 302022007143-9

(51) **LOC (15) Cl.** **30-11**

(52) **U.S. Cl.**

USPC **D30/161**

(58) **Field of Classification Search**

USPC D24/176, 180, 182, 184, 231; D8/16, 19, D8/306, 315, 316, 321, 349, 354, 382, D8/385, 390, 395, 499
